Primary Examiner — Brett Miller*Assistant Examiner* — Sara Michie Pottenger(74) *Attorney, Agent, or Firm* — Platinum Intellectual Property(57) **CLAIM**

The ornamental design for a storage shed structure, as shown and described.

DESCRIPTION

FIG. 1 is a perspective view of a storage shed structure showing the claimed design;

FIG. 2 is a front view thereof;

FIG. 3 is a first-side elevational view thereof, the opposite side being a mirror image thereof;

FIG. 4 is a rear view thereof; and,

FIG. 5 is a top plan view thereof.
